UNITED STATES PATENT OFFICE

HARRY ALBERT GRIFFITHS, OF BIRMINGHAM, ENGLAND

PRESS FOR OPERATING ON METAL OR OTHER SHEETS

Application filed August 8, 1928, Serial No. 298,333, and in Great Britain August 27, 1927.

This invention has for its object to provide an improved press for use in the cutting out of circular blanks or other articles from metal or other sheets.

- 5 The invention comprises primarily the employment of a punch or similar tool which is situated below the level of the sheet and is arranged to operate in an upward, instead of the usual downward direction, in combination with means whereby the blanks or the like cut from the sheet are caused to move relatively to the machine in a direction opposite to that of the movement of the sheet.
- 10 Also the invention comprises the employment of means whereby the sheet is supported in an inclined position, the sheet being secured at its lower edge and moved in an upward transverse direction at the completion of each longitudinal movement through the sheet.
- 15 Further the invention comprises the combination and arrangement of parts herein-after described.
- 20 In the two accompanying sheets of explanatory drawings:—

Figure 1 is a side elevation showing diagrammatically one manner of applying my invention to a press for operating on metal sheets.

Figure 2 is a diagrammatic sectional plan and Figure 3 a diagrammatic sectional end view of the sheet supporting and transverse feeding mechanism.

25 In the construction of a machine as shown for cutting out circular blanks from a metal sheet, and flanging the same to form the body part or lid of a tin box, a punch or pair of punches *a* is or are arranged beneath the level of the metal sheet which is indicated by *b*, and are reciprocated in an upward and downward direction from a crank shaft *c* located beneath the punch or punches near the lower side of the machine. The dies *d* with which the punches co-operate are ar-

ranged above the punches. Between the punch and die is mounted a stripper plate *e* over which the sheet *b* to be operated on can traverse. Alongside the cutting tools is arranged a support for the sheet, the latter being held preferably in a downwardly inclined position. This support comprises a pair of slides *f*, *g*, movable on guides *h*, *i*, whereby motion in two directions at right angles to each other can be imparted to the sheet. The slide *f* is adapted in any convenient manner for the attachment to it of the sheet *b*. The slide *g* carries the guide *h*.

The longitudinal step by step movement of the sheet between the cutting tools along the guide *i* may be effected by means such as those described in the specifications of prior British Patents Nos. 237,112 and 277,505. The sheet is gripped at its lower edge by any suitable means. Preferably the means described in the prior British Patent No. 257,773 are employed for this purpose, with the addition of a small movable platform (not shown) which comes into operation to support the edge of the sheet while the latter is being gripped and subsequently remains out of action.

At the end of each complete longitudinal movement of the sheet, an upward, or transverse, movement is imparted to it for the purpose of bringing another portion of the sheet under the action of the tools. To effect this movement automatically, I arrange at opposite sides of the sheet support a pair of bars *j* on which a number of shoulders *k* are formed or provided at suitable distances apart. Preferably the collars on one bar are staggered in relation to those on the opposite bar, and the distance between any pair of collars on either bar is equal to one half of the movement required to be given to the sheet. Each of the bars *j* is mounted to slide at one end in a bearing *l*, and at the other end over a fixed bar *m*, the latter end of the bar *j* being made hollow to receive the bar *m*. Suitable reciprocatory movement is imparted to the

bars *j* by levers *n* actuated by a longitudinal shaft *o* which receives a rocking motion from any suitable part of the driving mechanism of the press at the completion of each longitudinal movement of the sheet along the bar *i*. In the arrangement shown the shaft *o* is rocked from a cam *p*, through a lever *q*, rod *r*, lever *s*, link *t* and lever *u*. As the cam shown moves the mechanism in one direction only, a spring *v* is provided to effect the return movement.

In combination with the transverse guide *h* is also arranged a rack *w* with which the pawl *x* can engage for preventing accidental return movement of the inclined sheet, and in combination with the slide *f* which moves on this guide are arranged a pair of pawls *y* for engaging the shoulders *k* on the bars *j* above mentioned. When the sheet occupies one extreme position as shown, one of the said pawls engages a shoulder on one of the bars, so that when the latter is actuated the required movement is imparted to the sheet for bringing it from one position to the next. When the sheet occupies the other extreme position, after the cutting out of another row of blanks, the other pawl comes into engagement with a shoulder on the other bar and another upward transverse movement is imparted to the sheet. The pawl *x* which engages the rack above mentioned can be released when required for the purpose of allowing the sheet *b* and slide *f* to be returned to its initial position.

It will be understood that the axis of each punch and die is at right angles to the plane of the sheet and is consequently inclined. After a blank has been cut out from the sheet it remains in contact with the punch until ejected, and after ejection it falls from the machine by gravity in a direction opposite to that of the movement of the sheet as indicated by the blanks which are shown by dotted lines at *z*, Figure 1.

The machine may be fitted with either a single punch and die, or with two or more punches and dies. When more than one punch and die are used as shown, the amount of longitudinal movement required to cut out a complete row of blanks is correspondingly reduced.

By this invention a variety of important practical advantages are obtained. For example, by arranging the punch beneath the level of the sheet, I am able to avoid, without the provision of any special devices, the trapping of portions of the scrap in the tools. This advantage is supplemented by the fact that the punchings and the sheet move in opposite directions, and by this fact I also am able to avoid entanglement of the punchings with the scrap. Further, by arranging the sheet to move in an upward direction under the action of a gripper acting on its lower edge, I am able to relieve the attendant of

a good deal of laborious work which is usually incidental to the operation of machines of this kind. Also considerable simplification can be effected in the construction and arrangement of the various mechanical movements of the machine.

The invention is not limited to any particular subordinate details, as these may be varied to meet different requirements. It will be understood that this invention is concerned mainly with the transverse feeding mechanism and the arrangement of the tools, and consequently for the sake of simplicity and clearness only sufficient of the machine has been illustrated to elucidate the invention. I have already mentioned how the longitudinal feeding motions may be produced and how the sheets may be attached to the slide *f*.

Having thus described my invention what I claim as new and desire to secure by Letters Patent is:—

1. In presses for operating on metal and other sheets, the combination comprising a movable tool which is situated below the level of the sheet and is arranged to operate in an upward direction, means for moving the sheet upwardly at an inclination and the movable tool being arranged to operate at an angle to the vertical and perpendicularly to the sheet whereby the parts cut from the sheet are caused to move relatively to the press in a direction opposite to the movement of the sheet, substantially as described.

2. In presses as claimed in claim 1, an inclined support for the sheet, means whereby the sheet is held at its lower edge, and means whereby intermittent feeding movements are imparted to the sheet in an upward direction on the support, substantially as described.

3. In presses as claimed in claim 1, the combination comprising a pair of slides and guides, one of which is at right angles to the other, a sheet carrier in combination with one of the slides, a pair of movable bars, means for releasably and operably connecting the bars and sheet carrier together, and means for imparting sheet feeding movements to the said movable bars, substantially as described.

4. In presses as claimed in claim 1, the combination comprising a pair of slides and guides, one of which is at right angles to the other, a sheet carrier in combination with one of the slides, a pair of movable bars, means for detachably connecting the bars and sheet carrier together, means for imparting sheet feeding movements to the said movable bars, and detachable engaging means in combination with the sheet carrying slide and guide whereby unintentional movement of the sheet is prevented, substantially as described.

5. In presses for operating on metal and other sheets, the combination comprising an inclined sheet support, an upwardly acting

5 punch having its axis inclined and arranged perpendicularly to the sheet on the support and acting against the under surface of the sheet so that parts cut from the sheet will pass downwardly, and means for intermittently feeding the sheet upwardly on the support, substantially as and for the purposes set forth.

In testimony whereof I have signed my name to this specification.

10 HARRY ALBERT GRIFFITHS.
